HYDRAULIC TAPPET

Charles E. Johnson, North Muskegon, Mich.

Application December 21, 1938, Serial No. 247,071

2 Claims. (Cl. 123—90)

This invention relates to hydraulic tappets and is particularly concerned with the construction of a tappet which is held in an inverted or substantially inverted position and used in connection with those cylinders of engines of certain types which are inverted from the normal upright vertical position which most engines occupy. In some cases, as for example in radial engines used in airplanes and in other places, a cylinder may be vertical or perhaps inclined to the vertical with the combustion chamber at the lower end of the cylinder and the crank case above it, and it is with engines of such type that the tappet construction of the present invention is concerned.

Such air as is carried by the oil from the engine to and within the bodies of hydraulic tappets, should be separated from the oil prior to the entrance of the oil into the pressure or hydraulic chamber of the tappet, and the present invention is concerned with a simple construction which will insure such air separation, the tappet being inverted in position with respect to the position occupied by tappets in the ordinary vertical or substantially vertical cylinder engines.

An understanding of the invention may be had from the following description, taken in connection with the accompanying drawing, in which:

Fig. 1 is a vertical section through an inverted cylinder structure to which my invention is applicable.

Fig. 2 is a similar vertical section through the tappet, and

Fig. 3 is a horizontal section on the plane of line 3—3 of Fig. 2, looking upwardly in the direction indicated.

Like reference characters refer to like parts in the different figures of the drawing.

The engine block includes the engine cylinder 1, in which a piston 2 is reciprocable, having ports as at 3 for the entrance of the fuel mixture and for the escape of the exhaust gases. At the lower end of each port leading into the combustion chamber of the engine cylinder is a valve 4 having an upwardly extending stem 5, acted upon by a coiled pressure spring 6 to normally hold the valve in closed position. The cam shaft 7 with the cams 8 thereon for opening the valves on rotation of the shaft is located above the tappet, the body of which is indicated at 9, and which is interposed between a cam and the upper end of the valve stem 5.

The tappet body 9 is guided vertically in a

vertical opening made in a guide sleeve portion 10 of the engine block. The body has a continuous annular groove 11 around its outer side between its upper and lower ends, to which oil under pressure is carried by branch conduits 12 from a main oil conduit 13 into which the oil is pumped by the engine pump, there being a branch 12 from the main conduit for each of the tappets. The body 9 is closed at its upper end as indicated at 14, cam 8 bearing thereagainst. The body is hollow and in the lower end a hollow piston structure 15 is mounted, the lower end being closed by a hardened wear plate 16 against which the upper end of the valve stem bears. The piston 15 has an outstanding annular flange 17, the diameter of which is slightly less than the interior diameter of the body 9. There is a split ring 18 above the flange 17 for guarding against any excess passage of oil in the same manner as in my Patent No. 2,090,795, issued August 24, 1937.

Within the tappet body and between its upper and lower ends is a valve cage member and partition 19 having an outwardly extending flange 20 which has a press-fit within the body as shown, the upper end of the member 19 having an opening for oil passage closed at its lower side by a flat plate valve 21 which is held normally in an upper closed position, a light spring 22 resting at its lower end on a combined base plate spring cage member 23. A relatively heavy coiled compression spring 24 is located between the split ring 18 and the plate 23, as shown. This structure is substantially the same as that shown in my patent above identified and in my pending application Serial No. 122,234, filed January 25, 1937, now Patent No. 2,145,484, issued January 31, 1939.

The upper space within the tappet body 9 provides an oil receiving chamber 25 into which the oil passes from the groove 11. In one side of the tappet body an inset elongated boss 26 is cast extending upwardly and inwardly and which, lengthwise thereof, has an upwardly and inwardly extending passage 27 providing a communicating conduit between the groove 11 and oil chamber 25. It is evident that the oil must be passed upwardly through the passage 27 and be delivered to the chamber 25 near its upper end. A small opening or passage 28 is drilled or otherwise made through the wall of the body 9 at its upper end, such passage leading from the chamber 25 to the outside end serving to carry off any air which naturally will separate and rise vertically from the body of oil within 55

the chamber 25 above the upper level thereof and be carried outwardly through the passage at 28.

With this invention the oil supply in a relatively considerable body is maintained constant in the chamber 25 and is held therein an appreciable and amply sufficient time for air delivered thereto with the oil at the upper part of the chamber to separate from the oil and pass outwardly through the passage at 28, whereby any oil that passes the valve 21 will be substantially if not entirely free of air.

The construction described, while of a simple nature, is practical, easily manufactured and efficiently serves the purpose for which it is designed. The invention is defined in the appended claims and is to be considered comprehensive of all forms of structure coming within their scope.

I claim:

1. A hollow valve tappet body closed at its upper end, a partition having a passage therethrough within and between the ends of the tappet body providing an oil receiving chamber above the partition and in the upper end of said body, a spring actuated valve closing said opening in the partition, said tappet body having an

annular groove around its outer side between its ends and an upwardly extending passage leading from said groove into said chamber and communicating therewith, the upper end of said passage being located near the closed upper end of the body, and a wall of said tappet body near the upper end thereof having a passage therethrough of small cross sectional area for the escape of air.

2. A tappet construction comprising, a hollow tappet body closed at its upper end, a valved partition within and across the body between its ends, thereby providing an oil receiving chamber above the partition and in the upper end of the body, said tappet body having an annular groove around and between its ends and provided with an inset vertically extending boss at the inner side of the vertical wall of said body, the end of said boss terminating a short distance below the closed upper end of the body and said boss having a longitudinal upwardly extending passage from said groove to the upper end of the boss, and a wall of said tappet having a limited air passing opening therethrough communicating with said oil chamber closely adjacent its upper end.

CHARLES E. JOHNSON.
